Specification of Letters Patent.

Patented Oct. 5, 1909.

Application filed August 7, 1906. Serial No. 329,578.

To all whom it may concern:

Be it known that I, WILLIAM LEIVESLEY, a subject of the King of Great Britain and Ireland, residing at Eclipse street, Springsure, in the county of Denison, in the divisional district of Leichhardt, in the State of Queensland, Commonwealth of Australia, have invented certain new and useful Improvements in Telegraph Systems, of which the following is a specification.

This invention relates to telegraph systems and combinations of apparatus used therewith.

In its broadest sense this invention comprises a system of switching and repeating, and although in regard to the purely instrumental parts, existing apparatus and well understood theories are used, it is peculiarly apart in its combination, arrangement, and working from other systems.

The object of the invention is to provide circuits and a simple combination of apparatus and switching gear to facilitate the transmission of messages direct to their destinations, over long lines and in a variety of directions, to permit any prearranged number of telegraph circuits to work with each other just as though they were all on one and the same circuit; to enable a number of stations on different lines, not ordinarily in direct communication, to communicate directly with each other without hand repetition. In newspaper messages the same news may be transmitted direct to its various destinations by one telegraphist by one operation of a telegraph key. This invention also allows of signaling four or more ways on the Morse system and at the same time may embrace or combine other systems. It provides for repeating direct on to main lines and different systems are enabled to work together and interchange signals harmoniously.

Other objects and advantages will be in part obvious and in part pointed out hereafter. But in order that this invention may be more fully understood and made comprehensible to those skilled in the art, diagrammatic drawings illustrating the same are appended as a part of this specification.

Figure 1 shows a cross-bar switch board in side elevation and partly in section. Only two of the lower bars are shown for convenience of illustration. Fig. 2 shows a repeater operating in accordance with the usual well known theories and is for work-

ing four or a lesser number of wires or lines and is capable of being reversed at the repeating station for transmission in the opposite direction. Fig. 3 illustrates the system indicated in Fig. 2 more particularly and is meant to show clearly the working parts in simple form and how the arrangements shown in the said Fig. 2 act. Fig. 4 shows an automatic combined repeater for working four or a lesser number of wires or lines and is capable of working in either direction without the need of an attendant to perform any hand switching. Fig. 5 illustrates the system indicated in Fig. 4, more particularly and is meant to show clearly the working parts in simple form and how the arrangements in the said Fig. 4 act. Fig. 6 illustrates how the ordinary Morse line relays and the lines connected therewith may be connected by means of the switch board for the simultaneous working of all the lines so associated.

On further reference to the drawings it will be seen that the switch board comprises metal bars 11 placed across each other. The upper bars are hereinafter called the upper series and the lower bars are hereinafter called the lower series. Between the upper series and the lower series is placed insulating material 12 (Fig. 1). At the crossing or point of intersection of each of the metal bars is a plug hole. The plug holes in the upper series are marked 13. The plug holes in the lower series are threaded as shown in Fig. 1 and marked 14. At each end of each bar is a terminal screw 15 and between the outer ends of each bar and its fellow are bridging connection spaces 16 to unite any bar of the same series to the next adjacent bar. By varying the connections of bars at the crossings or points of intersection by means of plugs and between the ends of the bars a variety of combinations may be made and the arrangement of any lines connected to the switch board may be diversified.

In combination with the foregoing two classes of plugs are used:—The first is a screw plug for connecting a bar of the upper series with a bar of the lower series and consists as shown in Fig. 1 of a milled knob or turning portion 17 composed of ebonite or similar insulating material and having below the same a head and a shank. The head is marked 18 and beneath it is a shoulder 19. The shank 20 is threaded as at 21.

The second class of plug has an entirely

plain and preferably tapering shank. It may be, however, of any suitable character, and is marked 22, (see Fig. 6).

Figs. 2, 3, 4 and 5: These figures indicate a combination of two systems of repeating apparatus with a simple means of using either one or the other as circumstances require. The change from Fig. 2 to Fig. 4 is effected by the placing of switches and plugs in the positions hereinafter described. The numerals 1, 2, 3, 4, in these figures represent telegraph lines earthed at distant stations (Morse systems). The plus signs show the positive lines or wires, and the minus signs or hyphens the negative lines or wires. The turning portions 17 of screw plugs indicate where a bar of the upper series is connected with a bar of the lower series. From the switch board extend four lines as shown. These communicate at 23, 24, 25 and 26 with the four segments of a four way plug switch 27. From each segment a line is led to three-way plug switches marked 28, 29, 30 and 31 respectively. From one of the segments of each of the three-way plug switches is led a wire to earth at 32, 33, 34 and 35. The relays 36 have the usual magnets and armatures with spring retraction and are influenced by main line currents. The armature contact points of the relays are marked at 37. Transmitting keys with circuit closing switches attached are shown at 38 and are for use of local attendant to transmit his own station's messages if desired. Galvanometers or current detectors are shown at 39. Manual switches are marked at 40. Plug holes at 41 are for admitting local sounders with their local batteries. Local sounder batteries are marked 42. Local sounders are marked at 43. For bridging contact points of the repeating transmitters or allowing same to be operative plug holes at 44 are provided. The contact points of the armatures of repeating transmitters are marked at 45. The repeating transmitters 46 have the usual magnets and armatures with spring retraction. Plug holes 47 are to make or break local relay armature contact point circuit. The local relays 48 have the usual magnets and armatures with spring retraction. The contact points of armatures of local relays are marked at 49. Local batteries are marked 50. Plug holes to make or break local circuits are marked at 51. It will be observed that the above instrumental parts all appear on both the right and left hand side of the apparatus, and the parts will, for convenience, be hereinafter referred to as either right hand or left hand dependent upon the side of the apparatus being referred to.

Fig. 2: In the condition as shown in the drawing Fig. 2 is arranged to repeat automatically in four directions on telegraph wires earthed at distant stations. When ar-

ranged as shown, the apparatus requires an attendant at hand to attend to the manual switches 40 to suit the requirements of distant stations. The right hand relay 36 is in condition to receive currents and signals from lines 4 and 3 and its armature which makes contact at 37 is in condition to repeat. Assume a key to be open on line 4 the right hand armature contact point 37 would stand open as shown. When the key alluded to be closed however, a current passes through the apertures from line 4 through the bar of the lower series connected thereto, through the connecting screw plug marked at 17 and outwardly along the first bar of the upper series and line connected thereto to 26, thence through the three-way plug switch 30 by means of the plug shown therein, via line to the left hand and closed manual switch 40, to right hand galvanometer 39 and key 38, right hand relay 36 whose armature makes contact at 37. The current passes through 44 on the left hand side by means of plug shown therein, through three-way plug switch 29 by means of plug shown therein, along line to second top bar of upper series, through connecting screw plug therein marked at 17 to bar of lower series line 3. So far it will be observed lines 4 and 3 are in direct communication. It will now be shown how currents and signals are conveyed to the lines 2 and 1. Contact at 37 having resulted from the current through magnet of right hand relay 36 a current would pass on the lines 2 and 1 from line 2 along bar of lower series connected thereto through connecting screw plug marked at 17, along bar of upper series and line connected thereto to 24 thence through three-way plug switch 28, right hand local sounder 43 and battery 42, through right hand relay armature contact point 37, right hand local relay 48, left hand galvanometer 39 and key 38, to left hand relay 36, through 44 on right hand side to and through three-way plug switch 31 to 23 along line to bottom bar of upper series, through screw plug marked at 17 to bar of lower series connecting line 1, and then to distant stations. In consequence of current passing as described all four lines receive signals at each movement of any key on lines 4 and 3. There is a further result in the apparatus locally. A current passing through magnet of left hand relay 36 attracts the armature to contact point 37. This action forms a local circuit from said left hand contact point 37 via left hand local relay 48, closed switch 40, left hand local sounder 43 and battery 42, back to the contact point. The current in this local circuit from the battery 42 operates through magnet of local sounder 43 whose armature is audible locally. (The right hand sounder 43 is not audible by reason of right hand manual switch 40 being open). Now should 120

any station on lines 2 and 1 require to transmit signals to lines 4 and 3 the telegraphist at such station on line 2 and 1 would break circuit by opening the key switch, 5 when signals from the opposite line 4 would cease to be recorded on left hand sounder 43. Under such condition the local attendant would close right hand manual switch 40 and open the left hand manual switch 40. 10 With switches now in this condition any station on lines 2 and 1 could transmit signals via left hand relay 36 in a manner as described on the opposite side of apparatus.

It may be noted that the armature of 15 either relay 36 repeats direct on to main line when either manual switch 40 is open. When both switches 40 are closed the signals on lines 4 and 3 do not pass to lines 2 and 1 nor vice versa; line 4 is simply in communication with line 3 direct, and line 2 in communication with line 1. Both sounders locally then become audible.

To work independently, any line may be earthed at the segment of its three-way plug 25 switch by inserting an extra plug to join earth at 32, 33, 34 or 35. Any line so earthed is not affected by signals from other lines, nor the signals of the repeating apparatus locally.

30 One line may be substituted for another and as the line wires and apparatus wires are shown affixed to switch board in Fig. 2 the method of substitution is as follows:— For clearness, call the upper part of the 35 switch board where numerals 1, 2, 3, 4, appear North, the lower part of switch board South; the right hand East, the left hand West. To transpose or exchange the places of lines 1 and 3 by way of example the screw 40 plug on bar connected to line 1 would be removed to two holes farther North, and the screw plug on bar connected to line 3 would be removed to two holes farther South. To exchange line wires the movement is either North or South in direction.

45 It will be seen that local circuits at 51 and 47 are broken. This is because they are not required when relays are to repeat direct on to main lines. Batteries 50 are therefore dormant. Plugs being out at 41, admit the local sounder batteries 42 to work sounders 43 as previously explained.

Fig. 3: It will be observed that this figure is, as hereinbefore stated, a simplification of the figure 2 and its working parts, as will be readily understood. It shows clearly how the relay armature repeats direct on to main line with plugs out of the body of Fig. 2 and is meant, as hereinbefore stated 60 for the purpose of more clearly understanding Fig. 2. An attendant locally is required to arrange the manual switches 40 to suit requirements of distant stations. To the segment of four-way plug switch 27 at 23, 65 24, 25, 26 line wires are attached, which

line wires are earthed at four distant stations. Assuming a distant station on line 3 opened a key thereby breaking circuit, the right and left hand relay armature contact points 37 would be open as shown. On closing such key a current would pass via, 23, right hand galvanometer 39, through the closed right hand manual switch 40 and relay 36, right hand key 38 to 26, line 4 and earth at distant station. The result would be that magnet of right hand relay 36 would attract its armature to its contact point 37 which armature completes the circuit on the lines 2, 3. The armature alluded to performs the office of key at the right hand contact point 37. A current would pass from line 1 via, 24, left hand relay 36, right hand contact point 37, right hand battery 42, magnet of right hand sounder 43, left hand galvanometer 39 and keys 38 to 25, and thus to distant stations on line 2.

It will be noticed right hand switch 40 is closed. This forms a local circuit whose sounder 43 and battery 42 are confined each time a current operates on the magnet of right hand relay 36 closing such local circuit, and the left hand sounder 43 is audible at each impulse of current. Should such left hand sounder cease to record signals, the attendant locally would close left hand manual switch 40, and open right hand manual switch 40, to allow any station on lines 1 and 2 to communicate signals as already described on the opposite side of apparatus. The right hand galvanometer 39 is simply to show the strength of current on lines 3 and 4. The left hand galvanometer 39 is simply to show the strength of current on lines 1 and 2.

Fig. 4: This figure constitutes an automatic repeater for four ways, without an attendant locally; certain plugs are inserted and others withdrawn from apparatus to form certain local circuits as will be hereinafter explained. Telegraph lines, earthed at distant stations, are joined to terminals of switch board and are marked 1, 2, 3, 4. If any key be opened on line 4 no current would be passing on main lines, and the apparatus would stand as shown in the drawing. The contact point 37 of the armature of right hand relay 36 is open as also is contact point 37 of the armature of left hand relay 36. The right hand repeating transmitter 46 at its armature contact point 45 is open, 120 but the left hand repeating transmitter 46 at its armature contact point 45 is closed.

Assuming now the distant key on line 4 be closed, a current passes from line 4, to bar of switch board in lower series connected thereto; through screw plug marked at 17, along bar of upper series and line connected thereto to section of four way plug switch at 26, via three way plug switch 30 to left hand manual switch 40, right hand galva-

nometer 39 (which shows the current), right hand key 38, magnet of right hand relay 36, left hand repeating transmitter contact 45, three way plug switch 29 to 25 through 5 segment of fourway switch 27 along line or wire to bar of upper series through screw plug 17 in switch board to bar of lower series connected to line 3 to distant stations. This shows that lines 4 and 3 are in direct 10 communication. It may be mentioned, when all keys are closed in every line's stations, the armature of relays 36 make contact at 37, so also armatures of repeating transmitters are closed at 45, locally. The effect 15 of the key on line 4 being closed causes the magnet of the right hand relay 36 to attract the armature to its contact point 37 which causes a closed local circuit via right hand local battery 50, magnet of right hand 20 repeating transmitter 46, plug at 51, back to 37. The magnet attracts the armature of right hand repeating transmitter to contact point 45, which forms a signal on lines 2 and 1, so that all four lines get the signal. It 25 has been explained that lines 4 and 3 are in direct communication, but the lines 2 and 1 get their signals by the right hand contact point 37 which acts and performs functions of a key operating the magnet of right 30 hand repeating transmitter 46. The armature of right hand repeating transmitter fills the office of key on the lines 2 and 1. The several armatures are detracted by springs which are adjusted to suit the re- 35 spective currents main or local. The right hand battery 50 gives a stronger influence in the upper local circuit, when the armature of right hand relay contacts at right hand contact point 37. It then embraces the one 40 magnet of right hand repeating transmitter 46 and consequently has a stronger influence than when the right hand contact point 37 is broken. The same battery then embraces the right hand magnet of local relay 48. 45 Now assume the distant key on line 4 is again opened, the armature of right hand relay 36 leaves its contact point 37 when the right hand battery 50 operates on magnet of right hand relay 48 which attracts its 50 armature to contact point 49. This closes a local circuit, without a battery, which bridges magnet of left hand relay 48 rendering it inoperative. The left hand battery 50 in consequence retains its strong in- 55 fluence on magnet of left hand repeating transmitter 46 which holds its armature firmly on its contact point 45. A course is thus provided by wire clear through the apparatus to allow the said key on line 4 to 60 make the next signal. Assume for clear- 65 ness, that the magnet of right hand relay 36 is on the eastern side of the apparatus, and the magnet of left hand relay 36 on the western side of apparatus. When the eastern side or lines affecting the eastern

side are signaling the following is the result:—An opening at right hand contact point 37 causes an opening at right hand contact point 45, and a closing at right hand contact point 49. A closing at 37 causes a closing at 45, and an opening at 49. An opening and closing of any key affecting the eastern side make such effects at every moment. Signals are recorded from the eastern side to the western side at the right 70 hand repeating transmitter armature contact point 45 which takes the function of a key. The western side, being constructed similarly to the eastern side, is capable of similar actions to those described. 75

Besides the plugs inserted in the three way plug switches 28, 29, 30, 31 to connect lines to apparatus, it will be observed that there are three other plugs inserted at 51, 41, 47, on each side of apparatus to form 80 local circuits. As batteries and sounders embraced by plugs 41 are not needed in the automatic arrangement shown in this figure their respective local circuits are bridged and inoperative. An extra plug at segments 85 of three way plug switches 28, 29, 30, 31 which lead to earth at 32, 33, 34, 35, would earth the lines attached to such three way plug switches so that one or all lines could be debarred from the influence of the repeating 90 apparatus. In this arrangement of Fig. 4 the manual switches 40 remain closed. The right hand galvanometer 39 shows the current on lines operating the right hand relay. The left hand galvanometer 39 shows the 95 current on the lines operating the left hand relay. The right hand key 38 operates the right hand relay and the lines attached thereto. The left hand key 38 operates the left hand relay and the lines attached thereto. 100 With all plugs out at 28, 29, 30 31, the apparatus in Fig. 4 is totally disconnected from main lines. Now by inserting a plug to join any two sections of four way plug switch 27 the lines so connected could 105 work direct with each other. Assuming the top end marked 1, 2, 3, 4 of switch board is north; and the lower, opposite end, south; by moving screw plugs north or south one line may be made to substitute another line 110 in a manner similar to that described for Fig. 2. The arrangement shown in Fig. 4 is purely automatic and requires no attendant. 115

Fig. 5: The apparatus shown in this figure operates exactly as described in Fig. 4 and is meant for the purpose of more clearly illustrating that figure. This Fig. 5 therefore occupies the same relationship to Fig. 4 as Fig. 3 does to Fig. 2, and should be read 120 with the description already given. 125

Fig. 6: It will be seen that in this figure the numerals 1, 2, 3, 4, 5, 6, 7, 8 indicate eight Morse telegraph lines. Line relays having the usual magnets and armatures 130

with spring retraction are marked 36 and the relay armature contact points are marked 37. Transmitting keys with circuit closing switches attached are shown at 38. Local batteries are marked 42. Galvanometers are marked 39. Sounders are marked 43. Plug holes to confine sounders are marked 41. Plug spaces to connect a pair of bars are marked 16. The turning portions 17 of 10 screw plugs show where a bar of the upper and a bar of the lower series are connected. Three way plug switches are marked 55. The points of communication of lines with said switches are marked 23 and 24, and 15 lines may be earthed locally at 32, 33, 34 35.

An attendant is required only to alter the position of the plug marked 22 to north or south on the switch board (that is assuming the upper part where lines are attached to 20 switch board is north and the lower opposite end south) to suit the station on any line wishing to signal the other.

As shown by the drawing with screw plugs connecting upper and lower series of 25 bars of switch board at 17, and one plug 22 the apparatus is in position for any station on lines 1 or 2 to signal to lines 3, 4, 5, 6, 7 8, which are earthed at distant stations. Assume that line 1 desires to transmit signals. As Fig. 6 is shown all keys on the 30 lines are closed. A current passing from line 1 enters locally the segment of its three way plug switch 55 at 24 thence to bar of lower series connected thereto through screw 35 plug and from 17 along the connected bar of upper series to plug at 22 back along adjacent bar joined at 22 to next screw plug marked at 17 passing through same to bar of lower series to galvanometer 39, magnet 40 of relay 36, to segment of the same three way plug switch 55, but at point marked 23, to earth at distant stations on line 2. Thus lines 1 and 2 are in direct communication with each other.

45 The main current as traced creates magnetism in magnet of relay 36 which attracts its armature to contact point 37 and such contact at 37 acts like a key on the next lines 3 and 4. Now to trace current on lines 3 and 50 4, start at segment of the three way plug switch 55 where line 3 is joined and marked 24, thence to connected bar of lower series to screw plug marked at 17, through screw plug and connected bar of upper series, 55 along wire to local battery 42, to contact point 37, along wire or line to magnet of sounder 43 along connected bar of upper series to screw plug through same and along connected bar of lower series to galvanometer 39, magnet of relay 36, to point marked 23 and then to distant stations on line 4. Lines 5 and 6 may be traced by similar letters and figures. Lines 7 and 8 may be traced by similar letters and figures. Now assume that 65 a station on line 1 opens a key, such key

breaks the circuit on line 1, the magnet of relay 36 on line 2 loses its magnetic power, consequently the armature loses contact at 37 which breaks lines 3 and 4. Lines 3 and 4 having lost current the magnet of relay 36 70 on line 4 loses magnetism and its armature 37 breaks circuit on lines 5 and 6. The lines 5 and 6 having lost current the magnet of relay 36 on line 6 loses magnetism and lines 7 and 8 are broken at 37. Thus the 8 lines 75 are void of current.

It will be seen that when a key breaks circuit all relay armatures, which act as keys for other lines, fly open in response to their respective armature springs and no 80 current flows on any line. When the key is closed on line 1 a current flows and all relay armatures are attracted to contact points marked 37. In Fig. 6 all armatures of relays are closed at 37 and it will be observed that 85 the armature at line 8 closes a local circuit via plug 22 on the right hand side of switch board. Trace the local circuit starting at armature contact point 37 of line 8 via local battery 42, along wire to screw plug marked 90 at 17, still along bar of upper series to plug 22, back along the top or uppermost bar, via screw plug marked at 17 to magnet of sounder 43 to 37 the starting point. The magnet of sounder 43 embraced in such local 95 circuit is the only one confined in a local circuit and its armature acts with every impulse of current and is audible locally. If while the key on line 1 be forming signals a key on another line breaks a circuit the 100 sounder described as being confined ceases to sound.

Any individual line may be earthed by inserting a plug in its respective three way 105 plug switch or commutator 55, so as to allow it to work independently of the other lines. The screw plug on the switch board may be moved to north or south to substitute other lines in substantially the same manner as hereinbefore described; or the said screw 110 plugs may be moved right or left to other crossings or points of intersection to form various combinations. The keys 38 are for use of the local attendant.

What I claim is:

1. In a telegraph system, a main circuit, a key and a principal relay therein, a second circuit, a repeater and a battery therein, a third circuit controlled by the repeater, a local relay in the second circuit, a circuit 120 controlled by the armature of such local relay, a contact controlled by the relay first mentioned, and means for permitting current from said battery to operate the repeater when said contact is closed, such closing operation simultaneously short-circuiting the local relay.

2. In a telegraph system, a main circuit, a key and a principal relay therein, a second circuit, a repeater and a battery therein, a 130

- third circuit controlled by the repeater, a local relay in the second circuit, a circuit controlled by the armature of such local relay, a second local relay connected with the 5 circuit last mentioned, a contact controlled by the armature of the relay first mentioned, means permitting current from said battery to operate the repeater when said contact is closed, such closing operation simultaneously 10 short-circuiting the local relay previously in circuit with the battery mentioned, said means permitting the last mentioned local relay when such contact is open to bridge the second local relay.
- 15 3. In a telegraph system, a switch comprising several divisions, a main circuit connected with two of such divisions, a key and principal relay in said circuit, a second circuit, a repeater and a battery therein, a third 20 circuit controlled by the repeater, a local relay in the second circuit, a circuit controlled by the armature of such local relay, a contact controlled by the relay first mentioned, and means permitting current from said battery 25 to operate the repeater when said contact is closed, such closing operation simultaneously short-circuiting the local relay.
4. In a telegraph system, a switch comprising several divisions, a main circuit connected with two of such divisions, a key and a principal relay in such circuit, a second circuit, a repeater and a battery therein, a third circuit controlled by the repeater, a local relay in the second circuit, a circuit controlled 30 by the armature of such local relay, a second local relay connected with the circuit last mentioned, a contact controlled by the armature of the relay first mentioned, means permitting current from said battery to operate 35 the repeater when said contact is closed, such closing operation simultaneously short-circuiting the local relay previously in circuit with the battery, said means permitting the last mentioned relay when such contact is 40 open to bridge the second local relay.
5. In a telegraph system, a plurality of main circuits, a key and a principal relay in each of said circuits, a plurality of associated circuits, a repeater and a battery in each of 45 said associated circuits, said repeater controlled by their corresponding principal relays, the armature contacts of each of such repeaters when closed permitting of the operation of the principal relay in a main circuit other than the one from which the repeater receives current, and independent means connected with each of the associated 50 circuits for causing the operation of the repeater of the main circuit last-mentioned when the armature contacts of the repeater 60 in the corresponding main circuit are open.
6. In a telegraph system, a plurality of main circuits, a key and a principal relay in each of said circuits, a plurality of associated circuits, armature contacts for each 65 of the principal relays, such contacts having connections across each of said associated circuits, a repeater and a battery in each of said associated circuits, a local relay in each of the circuits last mentioned, armature contacts for each local relay arranged to complete a circuit through the magnets of one 70 of the repeaters, the magnets of each of the local relays being connected across the circuit completed by the contacts of the other local relay, means permitting current from one of the batteries to operate one of the repeaters when the armature contacts of one of said principal relays are closed, such means operating to permit the local relay in 75 circuit with the battery last mentioned to bridge its corresponding local relay when such principal relay contacts are open, whereby the magnet of the other repeater receives a maximum current.
7. The combination with a switch board, comprising a plurality of series of bars, of a series of telegraph circuits connected with the ends of the bars, differential polar relays, repeating transmitters, transmitting keys, 80 batteries, differential repeating sounders connected with such circuits, and means for causing any one of the circuits to repeat on any of the other circuits.
8. In a multiplex telegraph, a switch-board comprising a plurality of series of bars, switches connected with the bars, transmitting keys connected with said switches, relays connected with the transmitting keys, galvanometers connected with the relays, local sounders connected with the relays, a duplex telegraphic circuit comprising a complete set of telegraphic instruments and including a differential polar relay, a differential neutral relay connected with the 90 switchboard, and means for causing any one of the relays to repeat onto any one of the other relays or onto the duplex circuit.
- In testimony whereof I affix my signature in the presence of two witnesses.
- WILLIAM LEIVESLEY.
